UNITED STATES PATENT OFFICE.

JOSEPH N. BORROUGHS, OF OAKLAND, CALIFORNIA.

TOWEL-HOLDER.

1,379,848.

Specification of Letters Patent. Patented May 31, 1921.

Application filed July 9, 1918. Serial No. 244,114.

To all whom it may concern:

Be it known that I, JOSEPH N. BORROUGHS, a citizen of the United States, residing at Oakland, in the county of Alameda and 5 State of California, have invented certain new and useful Improvements in Towel-Holders, of which the following is a specification.

My invention is an improved towel rack. 10 The invention is illustrated in the accompanying drawings which form a part of this specification and the appended claims.

Referring to the drawings:

Figure 1 is a front view of my towel rack.

15 Fig. 2 is a plan view thereof.

Fig. 3 is a rear view thereof.

Fig. 4 is a transverse section of the rack on line 4—4 of Fig. 3.

20 Fig. 5 is a sectional view of one end of the take up roller.

Fig. 6 is an end view of said end of the roller.

In the drawings, 1 indicates a frame which includes end walls 2 and 3, front wall 4 and 25 horizontal partition plate 5 extending between the end walls and formed with end flanges 6 secured to said end walls. Stud shaft 7 is journaled in wall 2 above partition 5 and shaft 8 is journaled in the wall 30 2 below partition 5 on which shafts are respectively secured on the inside of wall 2, intermeshing gear 9 and pinion 10. A stud 11 is reciprocally journaled in bearing 12 in end wall 3 in alinement with stud shaft 35 7. A conical engaging head 13 is provided on the inner end of stud shaft 7 for engaging a central conical socket 14 in one end of a towel reel 15, the other end of which reel is provided with a central conical socket 16.

40 to receive a conical engaging head 17 on the inner end of stud 11. A spring 18 is interposed between the end wall 3 and the head 17 for maintaining the heads 13 and 17 respectively in engagement with the reel

45 sockets 14 and 16 respectively whereby the reel is journaled in the frame 1 above partition 5. A towel 20 is wrapped around the reel 15 and extends outwardly from the rack through slot 21 in the front wall 4 and back

50 into the rack through slot 22 in said front wall below slot 21, and then between a corrugated roller 23 mounted on shaft 8 suitably journaled in bearings in walls 2 and 3, and a pressure roller 24 journaled in the 55 lower end of swinging arms 25 pivotally suspended on one of a pair of rods 27 ex-

tending from end wall 2 to end wall 3 and secured in said end walls.

A guide 30 is secured to the front wall 4 slightly above slot 22 for holding the lower 60 part of the exposed portion of the towel slightly out from said wall so that it may be easily grasped for use and for guiding the towel freely through said slot.

That portion of the towel extending 65 through the slots 21 and 22 is for use, and when used a clean portion of the towel is drawn off the reel 15 through slot 21, the used portion being drawn through rollers 23 and 24. The roller 23 is geared to draw 70 the towel off the reel 15 faster than the reel unwinds the towel, but this is not possible because the friction between the rollers 23 and 24 is slight and permits the rollers to slip over the towel and permits also the user 75 of the towel to hold the towel to prevent it being drawn through said rollers while unwinding a desired length from the reel. The partition 5 prevents the moist used portion of the towel from moistening the unused 80 portion on the reel.

A spring 35 is coiled around the shaft 8 within the roller 23 and is secured respectively at its ends to said shaft and to said roller so that the roller may be rotated 85 slightly backwardly with relation to the shaft 8 to allow a portion of the towel which might not have been used to be drawn back through slot 22 for use. When said portion of the towel has been used the spring 90 35 will rotate the roller 23 forwardly to its former position and draw said portion of the towel back to its former position.

Rollers 40 and 41 are journaled on the frame 1 inside of the front wall 4 in alinement with the slots 21 and 22 respectively over which rollers the towel 20 passes, said rollers preventing the edges of said slots from wearing or tearing the towel.

Having described my invention what I 100 claim as new and desire to secure by Letters Patent is:

1. A towel rack including a frame, a reel journaled in said frame, take-up means for the used part of the towel, and gearing between said reel and said take-up means whereby said take-up means is operated faster than said reel is unwound, said take-up means being constructed and arranged to permit the towel to slip therein. 110

2. A towel rack including a frame, a towel reel journaled in said frame, a front wall on

22
said frame provided with slots through which the towel passes, a take-up roller journaled in said frame over which the towel passes from one of said slots, a friction roller 5 engaging said take-up roller, a gear on the reel journal, and a pinion on the take-up roller journal meshing with said gear for rotating said take-up roller faster than said reel.

10 3. A towel rack including a frame, a towel reel journaled in said frame, a front wall on said frame provided with slots through which the towel passes, a take-up roller journaled in said frame over which the towel passes from one of said slots, a friction 15 roller engaging said take-up roller, a gear on the reel journal, a pinion on the take-up roller journal meshing with said gear for rotating said take-up roller faster than said reel, and means for permitting a slight backward rotation of said take-up roller.

4. A towel rack including a frame, a towel reel journaled in said frame, a front wall on said frame provided with slots through which the towel passes, a take-up roller journaled in said frame over which the towel passes from one of said slots, a friction 25 roller engaging said take-up roller, a gear on the reel journal, a pinion on the take-up roller journal meshing with said gear for rotating said take-up roller faster than said reel, and a spring against the tension of which the take-up roller may be rotated 30 slightly backward.

5. A towel rack including a frame, a towel reel on said frame, a take-up roller on said frame for said towel and a spring for holding the take-up roller in its normal forward position but permitting a slight backward movement of the roller. 40

6. A towel rack including a frame, a towel reel journaled in said frame, a front wall on said frame provided with slots through which the towel extends, said slots being spaced apart the distance of the normal 45 length of the exposed portion of the towel for use, a take-up roller journaled in said frame over which the towel passes from one of said slots, a friction roller engaging said take-up roller, a gear on the reel journal, and 50 a pinion on the take-up roller journal meshing with said gear.

7. A towel rack including a frame, a towel reel journaled in said frame, a front wall on said frame provided with slots through 55 which the towel extends, said slots being spaced apart the distance of the normal length of the exposed portion of the towel for use, a take-up roller journaled in said frame over which the towel passes from one 60 of said slots, a friction roller engaging said take-up roller, a gear on the reel journal, a pinion on the take-up roller journal meshing with said gear, and means to permit a slight 65 backward rotation of the take-up roller.

In testimony whereof I affix my signature.

JOSEPH N. BORROUGHS.
